Patented Nov. 23, 1915.

UNITED STATES PATENT OFFICE.

JOHN L. ROACH AND LANCE L. DAWSON, OF CHILDRESS, TEXAS.

BLOW-OFF COCK.

1,161,763.

Specification of Letters Patent. Patented Nov. 23, 1915.

Application filed June 3, 1914. Serial No. 842,799.

To all whom it may concern:

Be it known that we, JOHN L. ROACH and LANCE L. DAWSON, citizens of the United States, residing at Childress, in the county 5 of Childress and State of Texas, have invented new and useful Improvements in Blow-Off Cocks, of which the following is a specification.

Our present invention pertains to blow-off cocks for use on locomotive and other boilers; and it contemplates the provision 10 of a blow-off cock of such construction that access can be readily had to the main controlling valve for cleaning or grinding 15 thereof, without the liability of hot water or steam escaping from the boiler, and without the necessity of "killing" the fire and emptying the boiler of water as a condition precedent to removing the main valve for 20 the purposes stated, or for any other purpose.

The invention in all of its details will be 25 fully understood from the following description and claim when the same are read in connection with the drawings, accompanying and forming part of this specification, in which:

Figure 1 is a longitudinal section of the 30 blow-off cock constituting the best practical embodiment of our invention that we have as yet devised, and showing the main valve of the cock in partly closed position, and the auxiliary valve thereof in open position. Fig. 2 is a transverse section taken 35 in the plane indicated by the line 2—2 of Fig. 1, looking toward the left. Fig. 3 is a transverse section taken in the plane indicated by the line 3—3 of Fig. 1, looking toward the left, and showing one of the openings in the valve seat. Fig. 4 is a detail view showing the angular formation of the outer portion of the main-valve stem, and also showing the two stops and the lug between the same.

Similar numerals of reference designate 45 corresponding parts in all of the views of the drawings.

The body casing of our novel cock comprises an inner member 1, and an outer 50 member 2, the outer member being detachably connected with the inner member, preferably by a thread 3, as shown in Fig. 1. The inner member 1 is provided with a reduced and threaded portion 4 that is 55 threaded into the wall 5 of the water leg or other suitable part of the boiler. In the

said portion 4 is a valve seat 6, that is preferably beveled, as shown, and on said portion 4 and designed to rest within the boiler is a cage 5^a having openings 7, and 60 also having a diametrically disposed stop 8, the inner end of the said cage being open, as illustrated.

Movable in the cage 5^a and between the valve seat 6 and the stop 8 is the auxiliary 65 valve 9 of our cock, which auxiliary valve 9 is equipped with a stem 10.

The outer member 2 of the body casing is provided with an outlet 11, and is also provided with an inner end portion 12 in which 70 are two diametrically opposite openings 13. The inner end of the portion 12 forms a seat 14 for the main valve 15 of the cock, the said valve 15 comprising two wings arranged diametrically opposite each other so 75 that on rotary movement of the main valve 15 in one direction through about a quarter of a revolution, the wings will leave the openings 13 in communication with the interior of the member 1, while on a corresponding movement of the valve in the other direction the wings will effectually close the openings 13 to the interior of the member 1 and the boiler, and in that way prevent the 80 escape of steam and water through the outlet 11. The valve 15 is provided with a central aperture 16 that loosely receives the outer portion of the valve stem 10, and fixed with respect to and extending outwardly from the valve 15 is a stem 16^a. This stem 85 90 95 100 105 110

16^a is arranged snugly in a sleeve 17 of the member 2, and consequently it will be manifest that while the said stem 16^a can be readily turned about its axis in the sleeve 17, there is no liability of steam or hot water escaping between the stem and the sleeve and hence no necessity of employing packing. In the stem 16^a is a threaded bore and a plain or smooth bore to receive the threaded portion 18 and the smooth portion 19, respectively, of a stem that under normal conditions rests in the relative position shown, and serves by engaging the stem 10 to hold the auxiliary valve 9 away from its seat 6. At its outer end the stem that has the threaded portion 18 and the plain portion 19, is provided with a head 20, and at its inner side the said head bears against a washer 21, which serves to retain a handle 22 on the outer end portion of the valve stem 16^a, the said outer end portion, which is numbered 23, being preferably of angular form

in cross-section, so as to hold the handle against turning thereon.

At its inner side, the handle is provided with a lug 24, and this lug 24 is movable between stops 25 on the member 2 of the casing body, one of the said stops 25 being clearly shown in Fig. 1. In this connection it will be understood that when the lug 24 is against one of the stops 25, the openings 13 will be in full communication with the interior of the member 1, while when the lug 24 is against the other stop 25 the openings 13 are effectually closed to the interior of the member 1 and the interior of the boiler.

In the practical use of our novel blow-off cock, when it is desired to remove the main valve for cleaning or grinding, or for any other purpose and this without "killing" the fire and discharging the boiler of water, the stem having the plain and threaded portions is removed. When this is done, the pressure in the boiler is enabled to close the valve 9 against its seat 6, the pressure on the back of the valve being greater than on the front thereof, due to the space taken up by the stem 10. It will also be manifest that if for any reason the auxiliary valve 9 should fail to close, the main valve 15 can be opened after the removal of the stem therefrom, whereupon the momentum of the water in escaping through the blow-off cock will close the auxiliary valve 9.

The main valve 15 is removed with the member 2 of the casing body, when said member 2 is disconnected from the member 1. It will also be observed that after the member 2 is connected to the member 1 and the stem is replaced in the stem of the main valve and adjusted to the position shown in Fig. 1, it will operate to move the auxiliary valve 9 to and hold said valve 9 in the open position illustrated.

It will be gathered from the foregoing that our novel blow-off cock is simple, inexpensive and durable in construction, and that because of the fact that it is unnecessary to employ packing in the cock, the upkeep of the cock is practically nothing and engine failures, due to packing blowing out, are entirely eliminated.

The handle in closed position stands at forty five degrees to the right; the stop 25 in Fig. 1 being shown by dotted lines beyond the projection 24 on the handle.

Copies of this patent may be obtained for five cents each, by addressing the "Commissioner of Patents, Washington, D. C."

We prefer to provide the stem 10 with a 55 collar 9* to enable the momentum of water to better close the auxiliary valve when the main valve is opened after the removal of stem 19.

Having described our invention, what we 60 claim and desire to secure by Letters Patent, is:

The herein described blow-off cock, comprising an inner casing section having a cage, a valve seat at the outer end of the 65 cage and a stop in the inner portion of said cage, said section being constructed and arranged to be connected to a boiler wall and to project outwardly therefrom; an outer casing section detachably connected to the 70 inner section and having a valve seat at its inner end and an opening in said end and also having an outlet and a longitudinal sleeve; an auxiliary valve movable in the cage of the inner section between the stop 75 at the inner end of the cage and the seat at the outer end of the cage and having an outwardly extending stem; a revoluble main valve having a portion constructed and arranged in one position to close the opening 80 in the outer casing section and also having a stem removably-mounted in the sleeve of the outer casing section, said stem being provided with an outer portion of angular form 85 in cross-section and being also provided with a bore the outer portion of which is threaded and the inner portion of which is plain and receives the stem of the auxiliary valve; stops on the outer section of the casing; a 90 handle mounted on the outer angular portion of the main valve stem and having a lug movable between said stops; and a stem removably arranged in the bore of the main valve stem and having a threaded portion and a plain portion, said stem operating 95 against the stem of the auxiliary valve to hold the latter away from its seat, and being provided on its outer portion with means for holding the handle on the outer angular portion of the main-valve stem.

In testimony whereof we have hereunto set our hands in presence of two subscribing witnesses.

JOHN L. ROACH.
LANCE L. DAWSON.
